(57) **CLAIM**

The ornamental design for a surface roughness measuring device as shown and described.

DESCRIPTION

FIG. 1 is a front, left-side, top perspective view of a surface roughness measuring device, showing the new design; FIG. 2 is a front elevational view thereof; FIG. 3 is a rear elevational view thereof; FIG. 4 is a right-side elevational view thereof; FIG. 5 is a left-side elevational view thereof; FIG. 6 is a top plan view thereof; FIG. 7 is a bottom plan view thereof; and, FIG. 8 is a rear, left-side, bottom perspective view thereof. The broken lines depict parts of the surface roughness measuring device that form no part of the claimed design.
